(57) **CLAIM**

The ornamental design for a combined toiletbrush holder and toiletbrush, as shown and described.

DESCRIPTION

FIG. 1 is a top front right side perspective view of an assembly of a combined toiletbrush holder and a toiletbrush showing my new design;

FIG. 2 is a top plan view thereof;

FIG. 3 is a right side elevational view thereof, with the left side being a mirror image thereof;

FIG. 4 is a front elevational view thereof;

FIG. 5 is a rear elevational view thereof;

FIG. 6 is a bottom plan view thereof;

FIG. 7 is a top front right side perspective view of the toiletbrush; and,

FIG. 8 is a bottom front right side perspective view of the toiletbrush of FIG. 7.

The broken lines in FIGS. 7-8 showing certain details of the toiletbrush in dotted lines are for illustrative purposes only and do not form a part of the claimed design.

The toiletbrush is shown separately for clarity of illustration.
